UNITED STATES PATENT OFFICE.

ALFRED E. WALDEN, OF DETROIT, MICHIGAN, ASSIGNEE TO CHALMERS MOTOR COMPANY, OF DETROIT, MICHIGAN, A CORPORATION OF MICHIGAN.

FUEL-OIL-DELIVERY SYSTEM FOR MOTOR-VEHICLES.

1,111,335.

Specification of Letters Patent. Patented Sept. 22, 1914.

Application filed June 11, 1914. Serial No. 844,463.

To all whom it may concern:

Be it known that I, ALFRED E. WALDEN, a citizen of the United States of America, residing at Detroit, in the county of Wayne and State of Michigan, have invented certain new and useful Improvements in Fuel-Oil-Delivery Systems for Motor-Vehicles, of which the following is a specification, reference being had therein to the accompanying drawings.

The invention relates to liquid fuel delivery systems for motor vehicles of that type in which the main reservoir is located below the level of the carburetor and the liquid is elevated by pneumatic pressure.

It is the object of the invention to obtain a construction which insures the full delivery of the liquid as required, but which avoids danger of feeding when the engine is not in operation. To this end the invention comprises the construction as hereinafter set forth.

In the drawings:—Figure 1 is a diagrammatic representation of the system; and Fig. 2 is a vertical section through the elevated tank and the control mechanism.

A is the main fuel supply tank, which is conveniently located at a point below the level of the carburetor.

B is a hand air pump, which is connected by a conduit C to the upper portion of the tank A.

D is a mechanically-operated air pump driven from the engine (not shown) when the latter is in operation, and which is connected by a branch conduit E with the conduit C.

F is a small tank arranged above the level of the carburetor G and connected by a conduit H with the bottom of the tank A.

I is a conduit extending from the tank F to the carburetor, and J is a float within the tank F, which is connected with a lever mechanism K for operating a relief valve L in the branch C' of the conduit C. The arrangement is such that when the float J is lifted by the liquid in the tank F, it will open the valve L, and upon the falling of said float said valve will be permitted to

close.

With the construction as described in operation, to start the liquid feed the hand pump B is operated to place sufficient air pressure in the upper portion of the tank A to force the liquid therefrom upward

through the conduit H and to fill the small tank F from which the liquid is supplied to the carburetor. Whenever the engine is in operation the mechanically-driven pump D will continue to supply compressed air, which is distributed through the conduit E to the conduit C and to the tank A. The air thus supplied is in excess of that required for the feeding of the oil at the normal rate of consumption, and therefore the air pressure in the system will rise to an abnormally high point. Such a result is, however, prevented by the operation of the float J, which, rising, will operate the lever K and open the relief valve L which is provided with relief ports L'. This will vent the air conduit C and provide an escape for the excess pressure. In normal operation the valve L will be held partially open so as to reduce the air pressure in the system to just that point which is desirable for the feeding of the oil. Any excess of pressure is prevented by the wider opening of the valve, while any drop in pressure is prevented by the closing of the valve, so that in effect this valve forms a pressure regulator for maintaining a constant pressure of air in the system.

It is obvious that when the engine is not running the air pressure will be exhausted so that the oil cannot be elevated from the tank A to the tank F. Thus if there is any leak through the carburetor the only waste will be the relatively small volume of the tank F and not the larger volume of the tank A.

What I claim as my invention is:—

1. The combination with a main tank, of an auxiliary tank at a higher level, a delivery conduit from said main tank to said auxiliary tank, means for supplying air under pressure to said main tank to elevate the oil therefrom to the auxiliary tank, and means controlled by the level of the oil in the auxiliary tank for regulating the air pressure.

2. The combination with a main tank, of an auxiliary tank at a higher level, a conduit for delivering oil from said main tank to said auxiliary tank, means for pumping air to develop a pressure on the oil in said main tank for elevating the same to the auxiliary tank, and means controlled by the level of the oil in said auxiliary tank for venting the air pressure.

3. The combination with a main tank, of an auxiliary tank at a higher level, a conduit connecting said tanks, means for pumping air and delivering the same to said main tank above the oil therein, a normally closed vent for the air pressure, and means operated by the rise of the level of the oil in said auxiliary tank for opening said vent.

4. The combination with a main tank, of an auxiliary tank at a higher level, a conduit connecting said tanks, an air pump, a conduit for delivering air from said pump to said main tank above the oil therein, said conduit also extending in proximity to said auxiliary tank, and a vent for said conduit opened by the rise of oil in said auxiliary tank above a predetermined level and closed by the falling of the oil below said level.

5. The combination with a main tank, of an auxiliary tank at a higher level, a conduit leading from the bottom of said main tank to the top of said auxiliary tank, a mechanically-driven air pump, a conduit connecting said pump to said main tank above the oil therein, said conduit also ex-

tending in proximity to said auxiliary tank, a vent valve communicating with said conduit and adjacent to said auxiliary tank, and a float in said auxiliary tank for opening said vent valve upon the rise of the oil above a predetermined level.

6. The combination with a main tank, of an auxiliary tank at a higher level, a conduit connecting said tanks, an air conduit connected to said main tank and extending in proximity to said auxiliary tank, a hand-operated pump for placing an initial air pressure in said conduit, a power-driven pump for maintaining the air pressure, a valve for venting the air pressure in said conduit adjacent to said auxiliary tank, and a float in said auxiliary tank for operating said vent valve.

In testimony whereof I affix my signature in presence of two witnesses.

ALFRED E. WALDEN.
